UNITED STATES PATENT OFFICE

CARL GESKE, OF GRAND RAPIDS, MICHIGAN, ASSIGNOR TO WINTERS & CRAMPTON COMPANY, OF GRANDVILLE, MICHIGAN, A CORPORATION OF MICHIGAN

HINGE CONSTRUCTION

Application filed July 7, 1930. Serial No. 466,013.

This invention relates to hinges used for mounting doors and available for use with many articles. The hinge construction of the present invention is particularly adapted for refrigerator use, though there are many other places where the hinge can be used, particularly where the doors rise with respect to the surface of the door frame, that is, the outer surface of the door is forward of the plane of the door frame or casing on which the door is mounted.

It is an object and purpose of the present invention to provide a novel hinge of pressed metal, so as to have an exceedingly attractive appearance and to present the appearance and effect of the hinges made from castings or forgings. The hinge comprises two essential hinge members pivotally connected together, one of the hinge members having one end portion extending between posts projecting from the other hinge member. Such posts are drawn from flat metal and are open at their inner adjacent sides and, with my invention of hinge, said open sides of the posts are closed by reinforcing and supporting members which better carry the hinge rod or pintle, affording a wider bearing surface and strengthening and reinforcing the structure so that it will have all the necessary strength that hinges for refrigerators require.

The invention consists in many novel constructive features and in organizations of parts for the production of a novel, practical, artistic and commercially successful hinge.

An understanding of the invention may be had from the following description taken in connection with the accompanying drawing, in which,

Fig. 1 is an elevation of the hinge made in accordance with my invention.

Fig. 2 is an elevation of the hinge from its inner side.

Fig. 3 is a section substantially on the plane of line 3—3 of Fig. 1.

Fig. 4 is a transverse section on a plane at right angles to the section shown in Fig. 3 and through the pivotal connection of the hinge parts, and

Fig. 5 is a perspective view of the auxiliary supporting and reinforcing member, one of

which is used with each of the posts on one of the hinge members.

Like reference characters refer to like parts in the different figures of the drawing.

In the construction of the hinge one of the hinge members, formed from flat metal, has a relatively large plate 1 of rectangular form and with inturned edge portions, from the intermediate portion of which the metal is pressed outwardly in a series of steps and finally formed into a section 2 which extends beyond a side of the hinge member 1, is curved inwardly as indicated at 3 and terminates in an inturned apron 4, while at each side edge the part 2 has two spaced sides 5 turned inwardly as best shown in Fig. 3. Each of said sides at points opposite each other is provided with an opening to pass the hinge pin or rod and the metal is pressed inwardly around said openings from said sides 5 making bearing collars or sleeves 6 (see Fig. 4).

The other hinge member 7 is also formed from sheet metal, is of rectangular form and has inturned flanges at its edges and is, likewise, pressed outwardly making the stepped portion 8 as shown. The metal is cut away at one side of the raised or stepped portion 8 and is turned upwardly and formed at each end of the opening into an outwardly extending post.

Each post is hollow and of substantially channel form, having a vertical outer side or web 9, with flanges 10 extending inwardly which are integrally connected by a curved top or outer end 11. The inner sides of the posts are open. At the open inner side of each post a strengthening and reinforcing member of sheet metal is inserted. It comprises a vertical side 12 with flanges 13 turned at right angles from the lower portion of the side 12, the upper portion 14 of said side 12 being curved and rounded to fit the curved and rounded outer ends 11 of the posts; and from said side 12 an outwardly extending sleeve or collar 15 projects around a hinge pin opening as shown in Figs. 4 and 5. These strengthening and reinforcing members are inserted at the open inner sides of the posts and have a press fit therein. When thus inserted the openings for passage of the

- hinge rod 16 in the sides 5 of the first hinge member, and in the sides 12 of the reinforcing members are in alinement and the sleeve 6 and 15 project oppositely from each other.
- 5 The outer sides of the posts described are also formed with openings alining with the other openings mentioned so that the hinge pin or rod 16 may be inserted therethrough and headed over to make a secure connection.
- 10 A hinge as thus constructed is of great strength and rigidity, presents a very attractive appearance and is very durable. The hinged joint is completely covered and disguised by the apron 4. The bearings provided by the sleeves 6 and 15 present wide surfaces for the pivot rod or pin with subsequent longer life and greater durability for the hinge. The reinforcing members have the effect substantially of making the posts in
- 15 effect the same as if they were solid and with the strength and durability of substantially solid posts.
- 20 The supporting and spacing members 17 at the inner sides of the hinge form the subject matter of a separate application filed by Alexander F. Winters on July 14, 1930, Serial No. 467,778 and forms no part of the present invention. The invention is defined in the appended claims and is to be considered comprehensive of all forms of structure coming within their scope.
- 25 I claim:
1. In a device of the character described, a sheet metal member having portions cut away and forced outwardly to form hollow posts of substantially channel form, sheet metal reinforcing members snugly fitting into the posts, a plate member having an integral section adapted to extend between the posts, and a hinge rod passing through the section and the posts whereby the plate member may pivot relative to the sheet metal member.
  2. An article as set forth consisting of a base member of rectangular form having a raised portion, channel shaped posts rigid with said raised portion spaced in juxtaposed relationship, a reinforcing sheet metal member comprising a side with flanges extending therefrom, said reinforcing members being snugly engaged interiorly one in each of said posts, said sides of the reinforcing members having sleeves therein, a hinge member having a section adapted to extend between the posts and a rod extending through said section and the said sleeves of the reinforcing members to pivotally mount the hinge member to the base member.
  3. A hinge comprising, a hinge member having spaced posts projecting therefrom open at their opposed sides, a second hinge member having a section thereof extending between the posts, plates fitting in and closing the open sides of said posts and a pivot pin extending through the posts, said plates and said section of the second hinge member.

4. A hinge comprising, a sheet metal hinge member having portions cut therefrom and extending away therefrom to form hollow posts closed at their outer ends and of substantially channel cross section, said posts being open at their opposed sides, sheet metal reinforcing members fitting into the posts and closing said open sides thereof, a second hinge member of sheet metal having an integral section provided with a section thereof extending between said posts, the outer side of said section being turned inwardly toward the first hinge member to make a covering apron and a hinge rod passing through the posts, the sheet metal members therein, and through the said section of the second hinge member, the hinge rod being covered from the outside by said apron.

5. In a device of the character described, a sheet metal member having portions forced outwardly to form hollow posts, sheet metal reinforcing members snugly fitting into the posts, a plate member having an integral section adapted to extend between the posts, and a hinge rod passing through the section and the posts whereby the plate member may pivot relative to the sheet metal member.

In testimony whereof I affix my signature.

CARL GESKE.
